ROY CROSS, OF KANSAS CITY, MISSOURI, ASSIGNOR TO CROSS DEVELOPMENT CORPORATION, OF WILMINGTON, DELAWARE, A CORPORATION OF DELAWARE

PROCESS FOR TREATING PETROLEUM HYDROCARBONS IN THE VAPOR PHASE

Application filed October 16, 1926. Serial No. 142,016.

This invention relates to improvements in a process for treating petroleum hydrocarbons in the vapor phase, and refers more particularly to the treatment of hydrocarbon vapors with alkaline earth metals, such as sodium, potassium, calcium, magnesium, strontium, barium and lithium.

This application is in part a continuation of an application Serial No. 119,171, filed June 28, 1926.

Among the objects of the invention are to provide a process or method in which oil is subjected to cracking conditions of temperature and pressure in a cracking process and the cracked products passed to a vaporizing stage wherein the lighter fractions are distilled from the highly heated oil, these distilled fractions being subjected to a dephlegmating action and passing thence to a treating stage where they are brought in intimate contact in counter-flow relation with an alkaline earth or alkali metal heated to a temperature above its melting point so that the treating material exists in a molten or liquid state; to provide a process in which the treating material is continuously circulated in counter-flow relation with the vapors, additional treating material being added as the liquid becomes spent or exhausted; to provide a process in which polymerized products are withdrawn from the treating stage and returned to be redistilled in a hotter zone of the system, while certain of the reaction products are diverted from the system, and in general to provide a process and apparatus hereinafter described.

The single figure is a diagrammatic side elevational view of an apparatus in which the process may be practiced.

Referring to the drawing, at 1 is shown a furnace consisting of a combustion compartment 2 and a tube compartment 3. In the latter compartment is positioned a heating coil 4 having a supply line 5 and a discharge line 6 communicating with a reaction chamber 7. The reaction chamber is preferably formed of a single ingot of forged steel, forged on a mandrel to size and having removable end plates to facilitate cleaning. The forged chamber is heavily insulated to

prevent loss of heat by radiation. A transfer line 8, in which is interposed a reducing valve 9 connects the chamber with an evaporator 10. The evaporator has an overhead vapor line 11 communicating with the lower portion of a dephlegmating tower 12 which is preferably of the bubble type. A draw off line 13 is connected into the bottom of the evaporator and is controlled by a valve 14 controlled by a liquid level regulating device, diagrammatically shown at 15. A similar mechanism controls the valve 16 interposed in the draw off pipe 17 connected into the bottom of the dephlegmating tower 12. The discharge line 13 terminates in a cooling coil positioned in the cooler 18, the discharge from the cooler being controlled by a valve 19. The discharge from the refluxing tower has connection with the tank 20, a pipe 21 leading from the tank to the suction side of the pump 22 whose discharge line 23 has connection with the supply line 5 to the heating coil.

The vapor line 24 connecting the top serves to discharge the vapors passing off from the top of the dephlegmator into the lower portion of the treating tower 25. This treating tower is also of the bubble type construction in which a series of pools are maintained by overflow standpipes and capped vapor risers which serve to cause the vapors passing upwardly through the tower to percolate through the pools of liquid. The top of the treating tower has a vapor connection 26 with the coil 27 in the condenser 28, the discharge end of the coil 27 terminating in a line 29 connected into the gas separator 30. This gas separator has a gas line 31 controlled by a valve 32 and a liquid draw off line 33 regulated by a valve 34.

For the circulation of the treating material a draw off line 35 is connected into the bottom of the treating tower 25. Through this line and connections the treating material is directed to a tank 36 from which the treating material is withdrawn by the pump 37 and returned to the tower through the pipe 38. A secondary line 39, controlled by a valve 39, connected into the pipe 35, serves as a means for supplying fresh treating material to the system as the material circulated

through the tower becomes exhausted or spent.

There is also arranged on the side of the tower and adjacent the lower liquid pool, a sight, or liquid gauge glass 40, in order that the level of the liquid can be seen.

A draw off line 41, controlled by a valve 42, is connected into the bottom of a treating tower in the form of a standpipe 42^a. This 10 standpipe arrangement is for the purpose of drawing off reaction products from the surface of the treating material. A second standpipe 43 in the bottom of the treating tower, has a continuation in the form of a 15 draw off line 44, which is connected to the suction side of the pump 45. By means of this pump polymers withdrawn from the top of the liquid body in the treating tower are pumped through the pipe 46 and discharged 20 into the bottom of the evaporator 10, where they are redistilled and the unvaporized material drawn off with the heavy bottom through the line 13.

In operation the oil is supplied from any 25 convenient source through the pipe 47 and pump 48, and pass through the line 49 and coil 50 positioned in the top of the tower 12, where it is subjected to the heat of the vapors in the tower. After being preheated in this 30 manner it is directed to the line 51, which communicates with the supply line 5, and is circulated thence through the heating coils of the furnace 1. In the furnace it is raised to a cracking temperature and in this condition 35 is passed to the reaction chamber where the cracking reaction instituted in the coils is completed, the temperature and pressure maintained upon the coils and reaction chamber will vary according to the oil undergoing 40 treatment. Normally temperatures ranging from 650° to 1000° F., and pressures from 500 pounds to 1000 pounds per square inch are usual. The oil on being discharged from the reaction chamber is introduced at reduced 45 pressure into the evaporator 10. The reduction of pressure, together with the contained heat of the oil, distills off the lighter fractions which pass overhead through the line 11 to the dephlegmating tower 12. The bottom 50 from the evaporator is diverted from the system after being cooled in the cooler 18.

In the dephlegmating tower the vapors are subjected to a refluxing action, the unvaporized material automatically withdrawn and recycled for retreatment by means of the 55 pump 22, while the vapors discharged from the top of the bubble tower are introduced into the lower portion of the treating tower. In the treating tower the vapors rise and are percolated through a plurality of pools of 60 treating liquid, thereby being brought in intimate contact with the liquid treating material. This treating material is introduced to 65 the system at a temperature sufficiently high

to maintain it in liquid state through the pipe 38.

A by-pass line 55, between the vapor pipe 24 and 26, serves to cut out the tower from the system when desirable, the vapors then passing directly from the tower 12 to the condenser 28. Vapors 53, 54 and 54^a govern the use of the by-pass line 55.

Connected into the upper portion of the tower 12 is a pipe 56 controlled by a valve 57, by means of which materials may be added to the refluxing tower. In bringing the system on stream, normally the treating tower is cut out until the apparatus has been brought to temperature and during this period a considerable quantity of distillate will have been produced. This distillate is returned and introduced into the refluxing stage, through the pipe 56, when the treating tower 25 is cut in order that the products will all be uniform in character.

Returning to the method of treating, when sufficient treating material has been introduced to the system the valve 39 in the line 38 is closed. The material is directed through pipe 61 to the tank 35^a which is insulated and heated by a steam coil 62.

As suggested, the heated liquid treating material is picked up by the pump 36 and forced through the line 37 into the treating tower at a point sufficiently high thereon to permit the accumulation of the material on a plurality of trays but at the same time leaving a fractionating zone beyond the treating stage. It may be desirable to have the treating stage and final fractionating stage in separate towers.

In the event it is necessary to isolate the tank 35^a from the system for cleaning purposes or otherwise, the valve in the line 61 and the valve 63 in the line between the tank 35^a and the pump 36 are closed and the treating material diverted directly from the draw off line 35 through the pipe 59 to the suction of the pump 36.

The tank 35^a is equipped with a draw off line 64, controlled by a valve 65. The equipment including the trap in the tower 25, through which the treating material is circulated, is heavily insulated to prevent loss of heat and is so arranged that it can be completely drained of the liquid treating material. From time to time, as the material becomes spent or exhausted, additional treating material may be introduced, or continuously circulated to and from the system.

The temperature of the vapors in the treating tower is sufficient to maintain the treating material in a liquid condition. If this is not the case, heat may be added to the bottom of the tower to keep the alkaline earth metal in liquid form, or by heat supplied to the tank 35^a.

In the description of the process the use of sodium as a treating material has been used

as typical, although it is understood that either of the other alkali or alkaline earth metals or mixtures thereof can be as well employed.

5 As previously suggested, the sight glass 40 is used for determining the liquid level in the bottom of the tower. From time to time the polymers or reaction products may be withdrawn through the line 41 and diverted from the system or recycled to the 10 evaporator for redistillation.

15 The treated vapor passing off from the top of the tower is subjected to a final condensing action and collected in the gas separator from 20 which the treated liquid is withdrawn through the valve 34, and the gaseous material through the valve 32.

25 In actual practice hydrocarbon vapors treated with metallic sodium, or other alkaline earth metals have been effectively purified to produce a water white sweet hydrocarbon distillate. The alkaline earths, particularly sodium, have an affinity for the sulphur compounds in the oil, and effectively remove these compounds with a very low percentage of loss of the volume of the treated oil.

30 Actual tests in which cracked distillates from the Mid-Continent and Californian fields, in which the oils were vaporized and the 35 vapors passed through successive pools of liquid sodium, produced a clear water white product which did not discolor on standing and passed both the "doctor" and "copper corrosion" tests.

35 As to sulphur removal, the alkali metals, such as potassium and sodium, are very active, though magnesium and calcium are more effective quantitatively. In some instances it is desirable to use the combination of the 40 metals in place of a single metal, the peculiar characteristics of the oils being treated more or less determining the metals most advantageously used as an effective purifier.

45 As suggested, the losses with this type of treatment are much less than those resulting from the usual methods of refining, particularly the acid and caustic treatment which is common to most refiners.

50 While the process of treating has been explained in connection with a high pressure, cracking process, it is as effective for the treatment of any distillate contaminated with sulphur compounds, whether a product of straight distillation, cracking or rerunning 55 equipment.

The lines through which the treating material is circulated are preferably heavily insulated.

I claim as my invention:

60 1. A method of purifying petroleum hydrocarbons, comprising the steps of subjecting the oil to cracking conditions of temperature and pressure, dephlegmating the vapors evolved and bringing them in intimate 65 contact with metallic sodium heated suffi-

ciently to exist in the liquid phase, continuously circulating the treating liquid in counterflow relation with the oil vapor, diverting separated polymers and reaction products and supply additional unused treating 70 metal with the exhaustion of the treating stream to effect continuous operation.

2. A process, such as that described in claim 1, in which selected portions of the polymerized products are recycled for re- 75 distillation in the system.

3. A process, such as that described in claim 1, in which the oil vapors treated by counter-flow contact with metallic sodium are at a temperature sufficiently high to maintain the treating material in molten or liquid 80 form during their contact therewith.

4. A continuous method of purifying petroleum hydrocarbons comprising the steps of vaporizing the hydrocarbons and bringing 85 the evolved vapors into intimate contact with metallic sodium heated sufficiently to exist in the liquid phase, continuously circulating the treating liquid in counterflow relation with the oil vapor, diverting separated polymers and reaction products and supplying 90 additional unused treating metal.

5. A continuous method of purifying petroleum hydrocarbons comprising the steps of vaporizing an oil and bringing the vapors 95 into intimate contact with metallic sodium heated sufficiently to exist in the liquid phase, continuously circulating the treating liquid in counterflow relation with the oil vapor, diverting separated polymers and reaction products and supplying additional treating metal to make up the diverted material, and recycling selected portions of the polymer 100 products to the oil being vaporized.
